CASING FOR A SUCTION CLEANER OR SIMILAR ARTICLE

Carroll M. Gantz, North Canton, Ohio, assignor to The Hoover Company, North Canton, Ohio, a corporation of Delaware

Filed Aug. 12, 1966, Ser. No. 3,454

Term of patent 14 years

(Cl. D9—2)

Fig. 1

Fig. 2

FIGURE 1 is a top plan view of a casing for a suction cleaner or similar article showing my new design,

FIGURES 3 and 4 are respectively front and rear elevational views thereof,

FIGURES 7 and 8 are respectively front and rear elevational views of the modified form of the casing shown in FIGURES 5 and 6.

The dominant features of my design reside in the portions of the drawings shown in full lines.

I claim:

The ornamental design for a casing for a suction cleaner or similar article, substantially as shown and described.
